UNITED STATES PATENT OFFICE.

WILHELM SCHOUREN, OF BRACHT, PRUSSIA, ASSIGNOR OF ONE-HALF TO
FELIX TONNAR, OF DÜLKEN, GERMANY.

APPARATUS FOR RINGING BELLS.

SPECIFICATION forming part of Letters Patent No. 392,072, dated October 30, 1888.

Application filed April 11, 1888. Serial No. 270,290. (No model.)

To all whom it may concern:

Be it known that I, WILHELM SCHOUREN, of the city of Bracht, in the Kingdom of Prussia and German Empire, have invented a certain new and useful Improvement in Apparatus for Ringing Bells of Bell-Towers, of which the following is a specification, reference being had to the accompanying drawings and to the letters of reference marked thereon.

10 This invention relates to an improved method of and apparatus for ringing the bells of bell-towers.

According to the method heretofore usually employed for ringing the bells of bell-towers, it was necessary to impart a reciprocating swinging movement to the bells themselves, which required a belfry of substantial and costly construction; but even then it sometimes happened, particularly in the case of 20 bells of extraordinary weight and size, that rather dangerous oscillations were imparted to the belfry.

To avoid this objection is the object of my invention; and it consists in the features of 25 construction and combination of devices, hereinafter described and claimed, for operating the clapper while the bell remains stationary, reference being made to the accompanying drawings, in which—

30 Figure 1 is an end view of my improved apparatus, partly in section. Fig. 2 is a similar side view thereof. Fig. 3 shows a detail. Fig. 4 is an end view, partly in section, illustrating modified means for imparting reciprocating motion to the clapper. Fig. 5 is a similar side view of Fig. 4. Figs. 6 and 7 are views similar to Figs. 4 and 5, respectively, showing a modified arrangement in the suspension of the clapper.

40 In Figs. 1 and 2 of the drawings the bell A is suspended rigidly in the belfry, and the clapper B forms no part of the bell, but is pivotally fastened by means of a bolt, d, between the upper ends of two arms, C, which enter 45 the bell, so that the free end of said clapper, on being swung to and fro, will strike against the inside of the stationary bell A at or near the lower rim of the latter—that is, near the same point at which the bells were heretofore 50 struck by their clappers suspended freely within and forming part of them. The ends

of the said arms opposite to those carrying the pivot d and the clapper hanging loosely thereon are fixed upon an oscillating shaft, D, journaled in suitable bearings, e, on top of a stand or frame-work, A², below the bell, and provided with a double-armed lever, G, rigidly fastened to the shaft D, and having a hook or other fastening device applied to each of its lever ends for the reception of two ropes or 60 chains, J, the other ends of which are attached to the two webs J' of a cranked shaft, J³, journaled in bearings J², and rotated by means of a hand-wheel, J⁴, and handle J⁵. The webs J', being arranged opposite each other, will, 65 on being rotated, act to pull downward first the one rope J and then the other, and, consequently, first the one end of the double-armed lever G and next the other, thus transmitting an oscillating motion to the shaft D, 70 carrying the fixed arms C, and thereby causing the latter and the clapper B, pivoted between their upper ends, to be swung regularly first in the one and next in the opposite direction, the clapper moving onward and striking 75 the bell every time that or somewhat after the oscillating shaft D and its fixed arms have arrived at their dead-point position.

Instead of attaching a rope to each end of the said double-armed lever G, one end of the 80 same may be provided with a weight, J⁶, Fig. 3, to counteract the strain of the rope J, attached to the opposite end of the said lever, the said rope having its other end attached to an eccentric (not shown) rotated by a handle 85 or in any suitable manner—such as in Fig. 2—the said eccentric pulling the rope J and the end of the lever G downward, while the weight J⁶ will act to raise the rope again and to bring its own end of the lever G down, thus causing 90 the required oscillating motion of the shaft D, carrying the said fixed arms C, with the clapper B, as heretofore described.

To insure a steady and regular motion, the oscillating shaft D carries a suspended pendulum, E, rigidly attached to the shaft and provided with a bob, F, capable of being adjusted and filled with suitable ponderous material, for the purpose of regulating or controlling the said motion and for assisting in overcom- 95 ing the dead-points in the return movement of the clapper.

In some cases I dispense with the means stated for imparting oscillating motion to the shaft D by hand and produce the said motion quite automatically. In such case, which is illustrated in Figs. 4 and 5 of the drawings, I arrange below the shaft to be oscillated another shaft, L, suitably journaled at L' in the frame-work below the bell A, and provided with two fixed ratchet-wheels, K K', and a fixed pulley, N, the latter being acted upon by a rope, O, carrying at its free end a weight, O', by the strain of which it is unwound from a drum, (not shown,) so that it will turn the pulley N, and thus impart rotary movement to the lower shaft, L, and to the ratchet-wheels K K', rigidly mounted thereon, in a reversed manner. During their rotation the hollowed teeth of the ratchet-wheels K K' will alternately come in contact with two pawls, m m', fixed upon the shaft D to be oscillated, the said pawls projecting therefrom in opposite directions, so that first the wheel K strikes against the pawl m and throws it forward, whereupon the other wheel, K', will act upon the other pawl, m', so that the said pawls, on coming in contact with their ratchet-wheels, will act at the same time to limit the extent of the oscillating movement thus produced of the shaft D and its arms C and clapper B, the said movement being likewise controlled in this arrangement by a pendulum, E, applied as before stated.

It will be seen that the pawl m, on striking against one of the teeth of the ratchet-wheel K, will arrest the rotary motion of the latter for a moment, but is then thrown forward again by the said wheel K, under the strain of the weighted rope O, so that the shaft D and the pendulum E will oscillate in an opposite direction until the pawl m', by coming in contact with one of the teeth of the ratchet-wheel K', will stop this oscillating motion of the shaft D and pendulum E again. The position of the ratchet-wheel K' on the shaft L being reversed to that of the ratchet-wheel K, the tooth of the former, under the strain of the weighted rope O, will raise the pawl m' at once again, so that the pendulum E will swing back and oscillate the shaft D in an opposite direction until its pawl m will strike against the next tooth of the ratchet-wheel K, whereupon the same play just described will be repeated.

It will be noticed that the pendulum E, after having come into its dead-point position by the pawl m' being arrested by the ratchet-wheel K', will, by means of its gravitation, assist in raising the said pawl m' out of contact with the said wheel K', so that it will be free to swing back again and bring the pawl m in contact with the ratchet-wheel K, imparting a fresh impulse to the said pawl, shaft D, and pendulum.

The modification of my invention, as illustrated in Figs. 6 and 7 of the drawings, shows that in lieu of the straight shaft D a cranked

shaft may as well be applied and the pendulum E suspended from the web r of such shaft. In this modification, which illustrates a preferable arrangement and combination of parts in accordance with my present invention, the motion of the pendulum is transmitted to the clapper B in the following manner—that is to say: Upon the foundation-plate carrying the bearings e of the pendulum-shaft D are fixed the two standards C*, in the upper ends of which is journaled the shaft d, to which are fixed the arm B' of the clapper B and the two levers d'. It will be noticed that in order to obtain an easier movement of the clapper B the latter is hinged to its arm B' at s, and, further, that the levers d' may be regarded practically as one two-armed lever connected by the intermediate portion of the shaft d, to which they are rigidly secured. The ends of these levers (or two-armed lever) d' are linked by means of the links C* to the ends of similar levers, d'', fixed upon the pendulum-shaft D. Both the levers d' and d'' assume a horizontal position when the arm B' of the clapper B is in its vertical position or at rest. The oscillating motion of the pendulum E and the rocking motion of the shaft D thereby produced, as hereinbefore described, cause, by means of the levers d'', fixed to the said shaft, and by means of the links C*, reciprocated by the latter, the levers (or two-armed lever) d' to be likewise raised and pulled downward alternately, and thus to transmit a rocking motion to the shaft d, carrying the fixed arm B', with the clapper B, so that the latter will strike the bell A alternately. The means for imparting the required oscillating motion to the shaft D, carrying the pendulum E, are not illustrated in this modification for the sake of clearness, and for the reason that they are the same as and do not differ as regards their function from those shown in the preceding figures, and as hereinbefore described. It will be noticed that in this modification the desired length of the stroke of the clapper B in proportion to the length of the stroke of the pendulum E allows of being regulated readily and nicely by choosing the length of the lever-arms d' in the proper proportion to that of the lever-arms d'', as it will be seen that by making the length of the arms d', as compared to the length of the arms d'', in a proportion of one to two, the angle of motion of the clapper B will be twice the size of the angle through which the pendulum E moves, so that by these means a long and powerful stroke of the clapper can already be obtained, even if the pendulum E is reciprocated only through a relatively small field of oscillation.

The bell-ringing apparatus, as herein described, allows of being constructed at a relatively small cost as compared to the means heretofore employed, and compares favorably with the latter in respect of simplicity of construction and appliance, and requires by far less power for being put and kept in operation,

while the body of the bell cannot, practically, be worn away, since the same, after years, may be turned slightly on its vertical axis, so as to bring other portions of its inner surface in contact with the swinging clapper.

Having thus described my invention, what I claim as new, and desire to secure by Letters Patent, is—

1. The combination, with a bell, of a rocking shaft, a weighted pendulum suspended from and oscillated by the rocking shaft and entirely disconnected from the bell, a freely-suspended clapper disconnected from the bell, and means for turning the rocking shaft to oscillate the pendulum, substantially as described.

2. The combination, with a bell, of a framework under the bell, a rock-shaft journaled on the frame-work, a weighted pendulum hung from the rock-shaft below the bell, a clapper supported by the rock-shaft and disconnected from the bell, and means for rocking the rock-shaft to operate the pendulum, substantially as described.

25 3. The combination, with a bell, of a rock-shaft supported below the bell, a weighted pendulum suspended from the shaft, two arms rising from said shaft into the bell and disconnected from the latter, a clapper freely suspended from the upper ends of the said arms, and means for rocking the said rock-shaft to oscillate the pendulum, substantially as described.

4. In an apparatus for ringing bells, a two-35 armed pendulum fulcrumed in the vertical axis of and below the body of the bell, the upper arm of said pendulum arranged to oscillate within the body of the bell, forming the center of oscillation for the clapper, in combination with means for imparting reciprocating motion to the said pendulum, substantially as and for the purpose specified.

5. The combination, with a bell, of a weighted oscillating pendulum fulcrumed below the mouth of the bell and having a portion rising 45 into the bell and disconnected therefrom, and a freely-suspended clapper hung from said rising portion, substantially as described.

6. In an apparatus for ringing bells, the rock-shaft D, carrying a fixed two-armed pendulum, the upper part of which extends within a fixed bell, in combination with an oscillating two-armed lever, G, mounted on the rock-shaft, and having the two suspended ropes J, substantially as and for the purpose specified. 50

7. In an apparatus for ringing bells, the rock-shaft D, carrying a fixed two-armed pendulum, the upper part of which extends within a fixed bell, in combination with an oscillating two-armed lever, G, mounted on the rock-shaft, 60 and having the two suspended ropes J, the lower ends of which are fastened to webs projecting in opposite directions from a cranked shaft, and means for rotating the latter, substantially as and for the purpose specified. 65

8. In an apparatus for ringing bells, the rock-shaft D, carrying a fixed two-armed pendulum, the upper part of which extends within a fixed bell, in combination with an oscillating two-armed lever, G, mounted on the rock-shaft, 70 and having the two suspended ropes J, the lower end of one of which carries a counter-weight, substantially as and for the purpose specified.

In testimony whereof I have signed my name 75 to this specification in the presence of two subscribing witnesses.

WILH. SCHOUREN.
